UNITED STATES PATENT OFFICE.

ROWAN THOMPSON FIFE DODDS, OF WELLAND, ONTARIO, CANADA.

MINE-VENTILATING SYSTEM.

Application filed September 6, 1924. Serial No. 736,325.

This invention relates to means for ventilating mines or other underground workings in which foul air, dust or explosive mixtures are liable to accumulate.

5 Ordinarily mines and the like are ventilated by induced draft, the air being put into movement by fires at the bottom of pits or stacks, or by suction fans. Such systems are very ineffective and many dead 10 areas usually exist in which there is no movement of air owing to the natural tendency of the air to follow the paths of least resistance to the outlet. My object therefore is to devise a ventilating system which 15 will provide ample ventilation at all parts of a mine, and which will enable the ventilation at any given part of the mine to be perfectly controlled.

I attain my object by means of the construction illustrated in the accompanying drawing which is a diagrammatical view showing part of a mine provided with my improved ventilating system.

20 1 are a series of mine chambers, which, as usual, communicate with a common exit passage 2. This, as usual, is connected by short cross passages 3 with a parallel passage 4 with which other chambers similar to 1—1 will usually communicate.

25 30 5 is a blast fan of suitable dimensions, which may be driven in any suitable manner. From this blast fan leads an air pipe 6, which is provided with branches 7 leading to the various chambers. A gate 8, which is normally closed, prevents back flow 35 through the exit 2.

35 40 45 From this arrangement it follows that every chamber in a series is independently supplied with air under pressure, which air passes to the common exit 2 and thence out at the other end, assuming the cross passages 3 to be closed. Ordinarily these passages will be provided with closures 9 having openings therein which may be stopped more or less at any time if desired by any suitable plugs 19. By this arrangement more or less foul air can be taken off from the exit passage 2 at any desired point and led back through the passage 4 to the head 50 of the mine.

55 Owing to frictional losses, it will usually be desirable in extensive workings to provide a booster arrangement so that all the work is not thrown on the fan 5. In the mine is therefore provided a suitable chamber 10 in which is located a booster fan 11,

which is driven in any suitable manner. With this chamber the air pipe 6 communicates, so that the fan will force through its exit air pipe 12 air passing into the chamber from the exit 2 as well as air passing from the pipe 6. An extension 13 of the exit passage is provided which is separated by the gate 14 from the exit passage 2, thus preventing back flow in the exit 13 to the fan 11. Any desired number of chambers 15 may be supplied from the pipe 12 through the branches 16.

A stop 17 is provided at the lower end of the passage 4 to prevent air escaping into the outlet passage 4.

Each branch 7 and each branch 16 is preferably provided with a control gate 18 by means of which the passage of air into the chambers 1 is regulated.

75 With this arrangement air under pressure is supplied to all parts of the workings, which expanding into the various chambers, gives a much better supply of air than is possible with the ordinary suction systems. Furthermore, perfect circulation in every part of the workings may be obtained and this circulation is under perfect control by means of the gates and other control means shown.

80 85 In my own prior Patents Nos. 1,376,082 of April 26th, 1921, and No. 1,434,879 of November 7th, 1922, I have set forth the importance of moisture in preventing explosions in dust laden air particularly in grain elevators and the like. A proper degree of moisture in the air of mines is also of great importance and if the air in the mine is normally too dry the air forced into it may be tempered in any desired way by the addition of moisture or by modifying its temperature. The air pressure employed may vary from 1 to 20 ozs. per inch according to circumstances. The smaller the air pipes the greater the pressure necessary to supply a sufficient quantity of air.

90 95 100 It will be understood, of course, that the outlets of the branch pipes will be varied by means of control gates 18 according to their distance from the source of supply to ensure equality of distribution.

105 What I claim is:

1. In a mine or the like having a plurality of chambers arranged in a series and having a common exit passage, an air pipe; 110 branches from the air pipe leading to the different chambers at points remote from

the communications with the exit passage; means for forcing air under pressure into the air pipe to flow in parallel through said chambers to the exit passage; means for controlling flow at one end of said passage; and means for venting said passage intermediate of its ends.

2. In a mine or the like having a plurality of chambers arranged in a series and having a common exit passage, an air pipe; branches from the air pipe leading to the different chambers at points remote from the communications with the exit passage; means for forcing air under pressure into the air pipe to flow in parallel through said chambers to the exit passage; means for controlling flow at one end of said passage; means for venting said passage intermediate of its ends; and means for controlling the flow in said passage intermediate of its ends.

3. In a mine or the like having a plurality of chambers arranged in a series and having a common exit passage; an air pipe; branches from the air pipe leading to the different chambers; means for forcing air under pressure into the air pipe; a blower chamber to which said air pipe leads and which also communicates with the exit passage; a second series of chambers arranged in a series and having a common exit passage in communication with the first mentioned exit passage; means for controlling the communication between the two passages; a blower in the blower chamber; an air pipe leading from said blower; and branches from said air pipe leading to the different chambers of the second series.

Signed at Niagara Falls, Ont., Aug. 12, 1924.
